UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

BAG-FASTENER.

1,113,978.

Specification of Letters Patent. Patented Oct. 20, 1914.

Application filed February 5, 1912. Serial No. 675,515.

To all whom it may concern:

Be it known that I, FRANZ A. FULLER, a citizen of the United States, residing in the city of Newark, in the county of Essex and State of New Jersey, have invented certain new and useful Improvements in Bag-Fasteners, of which the following is a full, clear, and exact description, such as will enable others skilled in the art to which it pertains to make, construct, and use the same, reference being had to the accompanying drawings, and to letters of reference marked thereon, forming a part of this specification.

The present invention has reference to improvements in that class of bag fasteners for bag frames, which are especially adapted for pocket books, satchels, purses and the like, and the invention relates more fully to a novel construction of a locking or holding catch connected with the frame sections thereof.

The main purpose of this invention is to provide a pocket book, purse or other frame, and its latch or catch, which shall be neat in appearance, and shall be of a simple, strong and durable construction, with a view of furnishing a bag or purse frame having a novel construction of spring-actuated holding catch or latch which can be easily manipulated.

The invention is clearly illustrated in the accompanying drawings, in which—

Figure 1 represents a front elevation of one form of bag or purse frame, with a catch or fastener embodying the principles of this invention. Fig. 2 represents a fragmentary longitudinal section, illustrating the arrangement of the spring clip and the spring for actuating the catch or fastener. Fig. 3 represents a vertical section taken on lines $x-x$ of Fig. 2. Fig. 4 represents a front elevation of the fastener with spring clip and spring attached. Fig. 5 represents a longitudinal view of the fastener partly in section; and Fig. 6 represents a perspective view of the plate, forming a part of the fastener, provided with an integral spring holding element.

Similar characters of reference are employed in all of the said above views, to indicate corresponding parts.

In the drawings, a and b indicate the usual pair of frame sections, (either chan-

neled or angled), which are pivotally connected at their lower end portions by means of suitable pins or rivets c , or they may be pivotally connected with each other in any other well-known manner. One of said frame sections as b is provided in its upper surface with a centrally arranged suitable opening for the reception of an extension formed on the catch member, to be presently described, and the other frame section as a is provided with a suitable nosing or projection d forced out from the metal from which said frame section is made, or any other suitable means may be provided, designed to be brought into holding engagement with a suitable indentation e or similar means formed in the under side of the catch member, to firmly secure the bag frame sections or members in locked position. The catch member which may be of any desired form or configuration consists preferably of the plate f , formed from a single flat piece of metal, provided with a downwardly projecting spring-holding member or portion g , extending at a right-angle, or approximately so, having formed thereon, holding means extending preferably the entire length of the downwardly projecting spring-holding member, by bending the metal thereof to form a bearing or channel h for the reception of the spring to be presently described. To provide a suitable finger piece or lift for the catch member, I have shown a chambered base h provided with integral extensions h' , mounted thereon, said extensions passing through suitable apertures in the plate f and closed down upon the under side of said plate. A convenient finger piece i is mounted upon said base, which may be secured thereto in any convenient or desired manner. The plate f is provided with an indentation e , so that when the bag frame sections are closed, the nosing or projection d will be received into said indentation e and firmly secure the bag frame sections in locked position. In order to hold said catch member in its normal initial position, I provide a suitable torsion spring j , one end of which is passed through the bearing h of the spring-holding member and rests against the under side of the frame section and the other end of which is secured to the spring clip l , now to be described. This spring clip in its preferred form, or when used in connection

with a frame member of channeled cross-section, as illustrated in Figs. 2 and 4 of the drawings, consists of a single piece of suitable metal channeled and of a dimension and shape approximating that of the channeled frame section to which it is secured by being forced therein. This clip is provided with a centrally-arranged depressed portion *m*, said portion being further provided with openings *n* through which one end of the spring passes, in which it is firmly held and prevented from rotation or accidental displacement. When the spring has in this manner been arranged in position, and secured to the spring clip and catch member, it, together with the spring holding means on the catch member, will limit the oscillatory movement of said catch member. In this manner, the movable catch will be retained in proper locking or holding position. When the catch member is raised, the projection *d* will become disengaged from the indentation *e* in the plate *f*, thereby placing the spring *j* under sufficient tension that when the operator releases his or her hand from the catch, the spring will again cause the said catch member to return to its normal position. The holding or locking operation of the catch member thus operatively connected with the frame section *b*, is caused by snapping or forcing the edge of the usual form of indentation *e* over the usual projection *d* upon the frame member *a* in the well-known manner.

Experience has demonstrated that the organization above described, is a practical and efficient one for accomplishing the ends sought by this invention. The construction, 40 may, however, be varied in detail by those skilled in such matters, without departing from the invention.

I claim:

1. The combination with a pair of jaws, one of which has a slot therein, of a catch member provided with a means of pivotal connection extending through the slot of said last mentioned jaw, and having interlocking engagement with the other jaw, said catch member having one side thereof provided with an integral extension folded back upon itself, the folded extension projecting through said slot, a channel-shaped spring clip frictionally secured to the inner portion of one of said jaws and in close proximity to the pivotal connection of said catch member, said clip being provided with apertures and a central depressed portion, and a torsion spring, one end of which is secured in the apertures and central depression of said clip and the other end of which is secured to and passes through the folded extension of the catch member.

2. The combination with a pair of jaws, a catch member mounted upon one of said jaws, and having interlocking engagement with the other jaw, a channel-shaped spring clip frictionally secured to the inner portion of one of said jaws and in close proximity to said catch member, said spring clip consisting of a single piece of metal channeled and provided with spring holding means, and a spring, one end of which passes through the spring-holding means of said clip and the other end of which is secured to the catch member.

This specification signed and witnessed this 31st day of January, 1912.

FRANZ A. FULLER.
